INSULATED JUG OR SIMILAR ARTICLE

Thomas W. Kaufman, 420 W. Main St.,
Carrollton, Ohio 44615

Filed Oct. 18, 1972, Ser. No. 298,620

Term of patent 14 years

Int. Cl. D7—01

U.S. Cl. D7—61

FIG. 3

FIG. 4

FIG. 1 is a top plan view of an insulated jug embodying my new design.

FIG. 2 is a side elevation thereof.

FIG. 3 is a side elevation at 90° to FIG. 2.

FIG. 4 is a bottom plan view.

I claim:

The ornamental design for an insulated jug or similar article, as shown.
